CLAIM

The ornamental design for a combined canvas mesh holder and yarn strand receptacles, as shown and described.

DESCRIPTION

FIG. 1 is a top plan view of a combined canvas mesh holder and yarn strand receptacles, showing my new design;

FIG. 2 is a right end elevational view, the left end elevational view being a mirror image thereof;

FIG. 3 is a front elevational view thereof;

FIG. 4 is a rear elevational view thereof; and,

FIG. 5 is a bottom plan view.
